UNITED STATES PATENT OFFICE

127,928

DESIGN FOR A PORTABLE ADJUSTABLE SCREEN

Benjamin Wellman, Milwaukee, Wis., assignor to Will Ross, Inc., Milwaukee, Wis., a corporation of Wisconsin

Application June 9, 1939, Serial No. 85,420

Term of patent 7 years

To all whom it may concern:

Be it known that I, Benjamin Wellman, a citizen of the United States residing at Milwaukee, in the county of Milwaukee and State of Wisconsin, have invented a new, original, and ornamental Design for Portable Adjustable Screen, of which the following is a specification, reference being had to the accompanying drawing, forming part thereof.

The single figure is a perspective view of a portable adjustable screen showing my new design.

The opposite side of the screen is similar in appearance to that of the side illustrated.

I claim:

The ornamental design for a portable adjustable screen, as shown and described.

BENJAMIN WELLMAN.
